FLOW GOVERNOR FOR FLUID OPERATED PUMPS

Clarence J. Coberly, Los Angeles, Calif., assignor
to Roko Corporation, Reno, Nev., a corpora-
tion of Nevada

Application May 6, 1938, Serial No. 206,427

7 Claims. (Cl. 103—46)

My invention relates to fluid operated deep well pump equipment, and more particularly to a fluid operated pump embodying a novel form of flow governing device.

5 My invention is an improvement over the devices shown in my copending Patents No. 2,119,-736, issued June 7, 1938, for Governed fluid operated pump, and No. 2,119,737, issued June 7, 1938, for System of operating fluid-operated pumps. 10 10 As shown in my above-numbered patents, fluid operated pump mechanisms for use in deep wells ordinarily include a fluid motor with a pump unit operatively connected to the fluid motor and adapted to pump oil from the well up through a production tube leading to the top of the well. For operating the mechanism, fluid such as oil is pumped under relatively high pressure through a tubing connected to the fluid motor. As long as the device is pumping oil from 15 the oil formation in the well, it will operate at a normal speed, but it often occurs that gas forms in or enters the pump unit so that instead of a liquid being pumped, the pump unit is operating against a compressible gas, the result being that 20 20 a material part of the pumping load is removed and the pump unit then races or operates at high speed until the gas is removed from the pump unit. Fluid operated deep well pumps, due to space limitations, are customarily of cylinder- 25 25 piston type, both the fluid motor and pump unit having pistons operating in suitable cylinders. When a pumping device of this character is allowed to race, damage and breakage of working parts are frequent, necessitating withdrawal and 30 30 replacement of parts.

My above copending applications in part cover providing such a fluid operated deep well pump with simple forms of governors for controlling the flow of the high pressure operating fluid to 35 35 the fluid motor thereof, by maintaining the volume of flow thereof below a predetermined maximum so as to prevent racing of the pump when the working load thereon decreases, the governors operating in response to changes in load condi- 40 40 tions existing in the pump unit. These prior flow governing devices of mine may be originally set for any predetermined maximum flow desired, within the limits of the devices, but in order to reset them they must either be removed from the 45 45 well by withdrawing the tubing on which they are suspended for surface adjustment, or the tubing must be rotated or otherwise moved to reset the devices for a different maximum flow condition. Readjustment of the governors is frequently necessary or desirable in view of frequent 50 50

changes in flow conditions in the wells, and either of the above modes of readjustment is sometimes impractical or undesirable under operating conditions.

Another disadvantage of my prior flow governors is that they cannot be removed from the well for cleaning or replacement of parts without disturbing the operation of the fluid operated pump. I have found that flow governors sometimes become fouled with sand, wax, or other 10 undesirable foreign substances which prevent the governors from functioning, usually resulting in the governors closing off entirely so as to prevent a flow of operating fluid to the pump, which heretofore has necessitated a pulling job, with 15 the attendant undesirable delays in production and expense incident thereto.

It is therefore a primary object of my present invention to provide a simple form of governor for controlling the flow of fluid under relatively 20 high pressure to a fluid operated pump, which may be readily installed in or removed from the well without moving the fluid operated pump or any of the tubing leading thereto. I prefer to accomplish this by providing a governor of such 25 small external diameter that it may be passed through the pressure fluid tubing into working position at any time after installation of the fluid operated pump, and by providing a seating mechanism whereby the governor will automatically 30 seat in working position in fluid-tight relation to a seat.

Other objects and advantages will be apparent from the following specification and the drawing, in which:

Fig. 1 is a diagrammatic view, partly in section, of my invention installed in a well.

Fig. 2 is a vertical sectional view of my invention, showing it in working position.

Referring to Fig. 1 of the drawing, I show an 40 oil well having a casing 10, the lower end of which is perforated as is well known in the art to permit well fluid to flow into the lower end of the casing from the producing formation. The upper end of the casing 10 is provided with a casing 45 head 11, as is well known in the art, suspended from which is a string of production tubing 12 which communicates at its upper end through the casing head with a discharge pipe 13, the lower end of the production tubing being provided with a check valve fitting 14 having a ball member 15 therein adapted to permit well fluid to flow from the casing 10 into the lower end thereof, and being provided at its upper end with a conical seat 16 which receives the lower end of 50 55

a fluid operated pump 17 in fluid-tight relation. Although any suitable type of fluid operated pump may be used, as is well known in the art, I prefer to use a fluid operated pump such as 5 shown and described in my earlier copending Patent 2,119,736, issued June 7, 1938, to which reference is hereby made.

As shown in Fig. 2, an upper fitting 18 of the fluid operated pump 17 is threadedly connected to a collar 19 which is in turn threaded to the lower end of a high pressure tubing 20 which extends upwardly through the casing 10 and through the casing head 11 to a suitable source of supply of high pressure operating fluid 15 (not shown). The collar 19 is provided with a bore 21 which is internally threaded to receive a tubular element 22 having a conical tip 23 secured to the upper end thereof.

Adapted to seat on the conical tip 23 of the 20 tubular element 22 is a flow governor 25 which provides the flow governing means of my invention. The flow governor 25 comprises a central tubular body 26 having an upper bore 27 and a lower bore 28 separated by a central body 25 portion 29. Secured to the upper end of the central tubular body 26 is an upper collar 30 having an internal diameter substantially smaller than the internal diameter of the upper bore 27, and to which is threaded a tubular fishing 30 member 31 having perforations 32 therein and having a post 33 formed integrally thereon or connected thereto having annular flanges 34 and having an eye member 35 at the upper end thereof. To the lower end of the central tubular body 26 is threaded a tapered seat element 36 having a conical seat 37 in the lower end thereof for engagement with the conical tip 23.

The central body portion 29 has a central bore 39 which is chambered out near its upper end to provide an annular chamber 40 and an annular wall 41. Vertical passages 42 are provided to communicate between the annular chamber 40 and the lower bore 28. The lower end of the central bore 39 is counterbored and threaded to receive a spring cup 43 against the lower end of which bears a compression spring 44. The upper end of the compression spring 44 bears against a circular plate element 45 which is adapted for slight vertical movement in a recess 46 formed between the upper end of the spring cup 43 and the central body portion 29. Engaging the circular plate element 45 is a pointed tip 47 of a piston rod element 48 adapted to slide in fluid-tight relation in the central bore 39. The piston rod element 48 is provided with an annular recess 50 near the upper end thereof of forming an upper shoulder 51 adjacent thereto and providing an annular space 52 between the recess and the annular wall 41. Secured to the upper end of the piston rod element 48 is a piston member 53 adapted for vertical movement in the upper bore 27 and having communicating helical grooves 54 and 55 in the outer surface thereof to provide a restricted passage communicating between the upper and lower faces of the piston member, the piston rod element 48 being provided with an axial passage 48a therethrough which permits high pressure operating fluid to flow into the lower end of the central bore 39 to assist in balancing the downwardly acting fluid pressure exerted on the upper face of the piston member 53. It is to be noted that the external diameter of the flow governor 25 is materially less than the internal diameter of the high pressure tubing 20 in order to insure

free passage of the flow governor through the tubing, which is an important feature of the invention.

In installing my invention in a well, the production tubing 12 with the check valve fitting 14 secured thereto is first run into the well, and the fluid operated pump 17 is then lowered into the well by means of the high pressure tubing 20 until the lower end of the pump seats in fluid-tight engagement with the conical seat 16. 5 It is sometimes preferable to seat the pump 17 in the fitting 14 and lower both the production tubing 12 and the high pressure tubing 20 into the well at the same time, and either mode of installation may be employed. The flow governor 15 25 may then be inserted into the upper end of the high pressure tubing 20 and lowered through the tubing to seated position, as shown in Fig. 2, by a suitable line 20a which may be a single strand of wire of small diameter and which passes 20 through a packing gland element 21a, which may be of any well known construction, in the line of the supply tubing. If the high pressure tubing 20 is filled with high pressure fluid, the flow governor 25 may be simply dropped therein and 25 allowed to descend by gravity, the high pressure fluid creating sufficient friction to prevent the governor from dropping too rapidly. Before the flow governor 25 is moved into the installed position shown in Fig. 2, it is set for any predetermined maximum flow therethrough by providing a compression spring 44 having the desired compressive strength or by substituting a piston member 53 having helical grooves 54 and 55 of any desired dimensions. In some cases it 35 may be desirable to operate the fluid operated pump 17 for a short time prior to installation of the flow governor 25 in order to determine the possible maximum production from the well so as to determine the proper setting of the governor 40 before installation therein.

In operation, after the flow governor 25 has been installed in the position shown in Fig. 2, high pressure fluid such as oil is forced downwardly through the high pressure tubing 20, it 45 passing through the perforations 32 and downwardly through the tubular fishing member 31 into the upper collar 30 of the flow governor 25. The high pressure fluid then flows through the helical grooves 54 and 55 of the piston member 50 53, which are so designed as to provide a pressure differential between the upper and lower faces of the piston member which is substantially equal to the maximum upward force which can be exerted by the compression spring 44 on the 55 lower end of the piston rod element 48 through the circular plate element 45. Consequently, the piston member 53 will move downwardly until the pressure differential thereacross is fully balanced by the upward force exerted by the 60 compression spring 44, at which time the piston will remain in equilibrium. The annular recess 50 on the piston rod element 48 and the annular wall 41 cooperate so that the annular space 52 therebetween forms a valve orifice through 65 which the high pressure fluid flows, the same being opened or closed to any degree by upward or downward movement, respectively, of the piston member 53. Thus, high pressure fluid flows through the annular space 52 into the annular chamber 40 and thence downwardly through the vertical passages 42 into the lower bore 28, from which it passes through the seat element 36 into the tubular element 22 and thence down- 70 75

wardly into the fluid operated pump 17 to operate the same.

If, for any reason, the pumping load on the fluid operated pump 17 decreases, for example, as a result of a substantial quantity of gas entering the fluid operated pump through the check valve fitting 14 from the well, the volume of flow of high pressure fluid downwardly to the pump tends to increase with the decrease in load, which in turn causes an increase in the pressure differential between the faces of the piston member 53 which overbalances the upward force exerted by the compression spring 44 and causes the piston member to move downwardly until such time as the pressure differential is again balanced by the spring 44, downward movement of the piston member bringing the shoulder 51 nearer to the annular wall 41 to restrict the cross-sectional area of the valve orifice formed by the annular space 52, and thus limiting the rate of flow of pressure fluid downwardly through the governor. It will thus be understood that any momentary increase in flow of pressure fluid through the high pressure tubing 20 causes an increase in pressure differential across the piston member 53, which immediately causes the piston member to move downwardly, thus throttling the flow through the valve orifice formed by the annular space 52.

When it is desired to reset the flow governor 25 so as to increase or decrease the maximum flow permitted therethrough, as, for example, when the natural flow of the well increases or decreases, a line and grapple (not shown) may be lowered through the high pressure tubing 20 so as to engage the eye member 35 or the annular flanges 34 of the flow governor, and the governor may then be raised through the high pressure tubing to the surface of the well where the compression on the compression spring 44 may be manually adjusted to provide for the desired maximum flow through the governor. The flow governor 25 may then be relowered, or dropped, through the high pressure tubing 20 to seat in working position as shown in Fig. 2 and as described above. Thus, it will be understood that the flow governor 25 shown herein may be readily withdrawn from the well at any time desired without disturbing the rest of the pumping equipment therein, which materially decreases the delays incident to removing the pump or tubing, or moving the same.

Although I have shown and described the preferred embodiment of my invention, it will be understood that I do not intend to be limited thereby but wish to be afforded the full scope of the following claims.

I claim as my invention:

1. In a fluid operated deep well pumping mechanism, the combination of: a pumping unit adapted to be placed in a well, said pumping unit comprising a fluid motor and a pump connected to said fluid motor so as to be driven thereby; a pressure fluid delivery pipe extending from a source of supply of pressure fluid downwardly through said well to said pumping unit for delivering said pressure fluid thereto; and a governor adapted to be passed through said delivery pipe in said well into working position adjacent said pumping unit to permit a flow of pressure fluid therethrough from said delivery pipe to said pumping unit, said governor controlling said flow of pressure fluid therethrough.

2. In a fluid operated deep well pumping mechanism, the combination of: a fluid operated

pumping unit disposed in a well; a tubular fluid inlet member extending from said pumping unit; a pressure fluid delivery pipe extending from a source of supply of pressure fluid downwardly through said well to said pumping unit for delivering said pressure fluid thereto; and a governor adapted to be passed through said delivery pipe in said well into operative connection with said tubular fluid inlet member, in which said governor connects said delivery pipe to said inlet member, said governor controlling the flow of pressure fluid to said pumping unit.

3. In a fluid operated deep well pumping mechanism, the combination of: a fluid operated pumping unit disposed in a well; a tubular fluid inlet member extending from said pumping unit; a pressure fluid delivery pipe extending from a source of supply of pressure fluid to said pumping unit for delivering said pressure fluid thereto; a governor adapted to be passed through said delivery pipe into operative connection with said tubular fluid inlet member, in which said governor connects said delivery pipe to said inlet member, said governor controlling the flow of pressure fluid to said pumping unit; and means for withdrawing said governor from said delivery pipe.

4. In a fluid operated deep well pumping mechanism, the combination of: a fluid operated pumping unit disposed in a well; a tubular fluid inlet member extending from said pumping unit having a seating connection thereon; a pressure fluid delivery pipe extending from a source of supply of pressure fluid to said pumping unit for delivering said pressure fluid thereto; and a governor having a seating element thereon, said governor being adapted to be passed through said delivery pipe to a position in which said seating element is seated in fluid-tight relation to said seating connection, said governor connecting said delivery pipe to said inlet member and controlling the flow of pressure fluid therethrough to said pumping unit.

5. In a fluid operated deep well pumping mechanism, the combination of: a fluid operated pumping unit disposed in a well; a tubular fluid inlet member extending from said pumping unit having a seating connection thereon; a pressure fluid delivery pipe extending from a source of supply of pressure fluid to said pumping unit for delivering said pressure fluid thereto; a governor having a seating element thereon, said governor being adapted to be passed through said delivery pipe to a position in which said seating element is seated in fluid-tight relation to said seating connection, said governor connecting said delivery pipe to said inlet member and controlling the flow of pressure fluid therethrough to said pumping unit; and means for withdrawing said governor from said delivery pipe without disturbing the position of said delivery pipe in the well.

6. A flow governor for controlling the flow of pressure fluid through a delivery pipe to a fluid operated pump in a well, the delivery pipe being connected to the pump to supply a flow of pressure fluid to the pump to operate the same, characterized by: the governor having an external diameter sufficiently smaller than the internal diameter of said delivery pipe so as to permit the governor to be passed downwardly through the delivery pipe to a position adjacent the pump, the governor communicating between the delivery pipe and the pump and controlling the flow of pressure fluid therethrough to the

pump; and means for forming a fluid-tight joint between the governor and the pump.

- 5 7. A flow governor for controlling the flow of pressure fluid through a delivery pipe to a fluid operated pump in a well, the delivery pipe being connected to the pump to supply a flow of pressure fluid to the pump to operate the same, characterized by: the governor having an external diameter sufficiently smaller than the internal diameter of said delivery pipe so as to per-

mit the governor to be passed downwardly through the delivery pipe to a position adjacent the pump, the governor communicating between the delivery pipe and the pump and controlling the flow of pressure fluid therethrough to the 5 pump; means for forming a fluid-tight joint between the governor and the pump; and means for withdrawing said governor from said delivery pipe.

CLARENCE J. COBERLY. 10
